(No Model.)

J. WALKER.
GATE.

No. 404,754.

Patented June 4, 1889.

UNITED STATES PATENT OFFICE.

JOSEPH WALKER, OF NEAR MANCHESTER, VIRGINIA.

GATE.

SPECIFICATION forming part of Letters Patent No. 404,754, dated June 4, 1889.

Application filed September 21, 1888. Serial No. 286,045. (No model.)

To all whom it may concern:

Be it known that I, JOSEPH WALKER, a citizen of the United States of America, residing near Manchester, in the county of Chesterfield and State of Virginia, have invented certain new and useful Improvements in Gates, of which the following is a specification, reference being had therein to the accompanying drawings.

10 This invention pertains to certain new and useful improvements in gates, having for its object the provision of a new and improved highly efficient gate composed of pivoted members and capable of being raised or lowered from either side into a vertical or horizontal position, and rigidly held or secured as against accidental displacement.

15 This invention therefore comprises the details of construction, combination, and arrangement of parts, substantially as herein-after fully set forth.

20 In the accompanying drawings, Figure 1 is a view in perspective of my improved gate. Fig. 2 is a sectional detail view thereof.

25 Referring to the drawings, A designates my improved gate, which is composed of an upper extended right-angular beam *a*, to which are pivotally secured the upper ends of hanger-bars *a'*, and to these bars *a'* are pivotally connected a series of parallel cross-bars *a²*, as shown. These parts are so constructed and arranged that the cross-bars *a²* will fold against the beam *a* when the main portion thereof occupies a vertical position.

30 B B are two parallel posts, between which the inner ends of cross-bars *a²* extend, while the outer ends of said cross-bars are designed to pass between two similar posts *b b*.

35 To either side of the right-angular beam *a* are secured plates *b' b'*, provided with slots *b²*, through which bolts *b³* are passed. By means of these slots and bolts said plates can be adjusted and secured at the desired point.

40 The gate is pivoted upon the posts B B by means of a short spindle or cross-rod C, passed through apertures of plates *b'* and resting in grooves or recesses formed in the tops of said posts. The gate A and its beam *a* are equally balanced, so that the same can be readily

45 raised and lowered. By shifting the fulcrum of beam *a* the center of gravity can be

changed and the gate held elevated at an angle, as is obvious. Two parallel posts D D are secured in rear of posts B, and between the same the right-angular end of beam *a* is 55 designed to move.

To a cross-piece *d* of these posts D is pivotally secured one end of a right-angular gravity-latch E, the main arm *d'* of which extends down to near the end of posts D, and is provided with two grooves or recesses *d² d³* for engaging beam *a*, the former for holding the gate down or closed and the latter for holding it up or opened.

45 F F are two levers centrally fulcrumed upon posts *f f*, and to their inner ends are secured pitmen or links *f' f'*, which are secured by bolts to the gate A.

50 To the outer ends of these levers F F are connected ropes or chains G G, each of which is passed over a roll *g*, attached to a short post *g'*, and after being passed around rollers *g²* *g³* of a latch-operating bar H is secured at its ends to levers *h h'*, fulcrumed upon a post *h''*. From the outer ends of these levers *h h'* depend short ropes or straps *h² h³*. 75

55 The latch-operating bar H above referred to is pivotally secured at *h³* to the gravity-latch E, and is passed through looped ends of straps or wires I I, depending from short 80 arms *i' i'* of posts *i'' i''*. To the outer ends of this bar H are secured short parallel strips *i² i³*, between which the rollers *g² g³* revolve.

60 From the foregoing description it will be seen that by grasping the rope or strap *h²* 85 of lever *h'* and pulling downward thereon the other end of said lever will pull on rope or chain G, and thus lower the outer end of the adjacent lever F and cause the elevation of gate A into a vertical position. When 90 the lever *h'* is being operated upon, the rope or chain G will cause the latch-operating bar H to move, and thus the groove or recess *d²* of the latch E is disengaged from the beam *a* and the same is free to move, and when its 95 outer right-angular portion reaches the extent of its movement the groove or recess *d³* of latch E will engage the same by gravity and hold the gate elevated in a vertical position.

100 It is obvious that after the operator has passed to that side of the gate opposite to the

one upon which he opened or raised the gate by pulling upon the lever *h* the gate can be lowered to its former position, the movement of said lever causing the gravity-latch 5 to be disengaged from the gate through the agency of bar *H*. By moving the looped ends of straps or wires *I* in either direction the same will effect the movement of bar *H* to a greater or less degree, as desired.

10 The parts of my gate are so arranged that the beam *a* is equally balanced, so that it can be easily and readily raised or lowered without any unnecessary labor and without fear of damage. When the gate is elevated or in 15 a vertical position, these plates *b'* can be adjusted, if desired, by simply loosening and then tightening the bolts *b*.

My invention, in addition to the foregoing advantages, is extremely simple, cheap, and 20 durable, and it will be seen that the same embodies further advantages in point of general efficiency and inexpensiveness.

I claim as my invention—

1. As an improvement in gates, the herein- 25 described gate having the upper pivoted right- angular beam, the posts between which said beam operates, and the gravity-latch pivotally secured to one of said posts and having grooves or recesses engaging said beam, sub- 30 stantially as set forth.

2. The gate having the upper pivoted beam, the posts *D D*, between which said beam op-

erates, the pivoted gravity-latch secured to one of said posts; and the latch-operating bar pivotally secured to said latch and loosely supported in position, substantially as described. 35

3. The gate having the pivoted beam, the posts *D D*, between which said beam operates, the latch pivotally secured to one of said posts, the operating-bar pivotally secured thereto, 40 and the ropes or chains for operating said bar, substantially as described.

4. The gate having the pivoted beam, the posts *D D*, between which said beam operates, the levers *F F*, secured to said gate at 45 their inner ends, the gravity-latch pivoted to one of said posts, the operating-bar pivoted to said latch, the levers *h h'*, and the ropes or chains connected to said latter levers and the levers *F F*, substantially as described. 50

5. The combination, with the gate having the pivoted beam and the posts *D D*, between which said beam operates, of the latch pivotally secured to one of said posts, the operating-bar pivoted to said latch, the guide-loops for supporting said bar, and the means for operating the latter at its outer ends, substantially as set forth. 55

In testimony whereof I affix my signature in presence of two witnesses.

JOSEPH WALKER.
